UNITED STATES PATENT OFFICE

132,377

DESIGN FOR A SWIMMING DEVICE

Walton Hall Smith, Kansas City, Mo.

Application February 5, 1941, Serial No. 98,761

Term of patent 14 years

To all whom it may concern:

Be it known that I, Walton Hall Smith, a citizen of the United States, residing at Kansas City, in the county of Jackson and State of Missouri, have invented a new, original, and ornamental Design for a Swimming Device, of which the following is a specification, reference being had to the accompanying drawing, forming part thereof.

In the drawing:

Fig. 1 is a perspective view of a swimming device showing my new design.

Fig. 2 is a plan view thereof.

Fig. 3 is a side elevational view thereof.

Fig. 4 is a front elevational view thereof.

I claim:

The ornamental design for a swimming device, as shown.

WALTON HALL SMITH.
